UNITED STATES PATENT OFFICE

WILLIS W. CASE, OF DENVER, COLORADO; NETTIE J. CASE ADMINISTRATRIX OF SAID
WILLIS W. CASE, DECEASED.

MELTING-FURNACE.

1,013,838.

Specification of Letters Patent.

Patented Jan. 2, 1912.

Application filed April 12, 1911. Serial No. 620,623.

To all whom it may concern:

Be it known that I, WILLIS W. CASE, a citizen of the United States, residing at Denver, in the county of Denver and State 5 of Colorado, have invented certain new and useful Improvements in Melting-Furnaces; and I do hereby declare the following to be a full, clear, and exact description of the invention, such as will enable others skilled 10 in the art to which it appertains to make and use the same.

This invention relates to melting furnaces especially adapted for melting metals, and has for its object to improve the heating 15 means disclosed in my former Patent No. 798,950, issued September 5, 1905.

To these ends the invention consists in the novel details of construction and combinations of parts more fully hereinafter 20 disclosed and particularly pointed out in the claims.

Referring to the accompanying drawings forming a part of this specification in which like numerals designate like parts in all the 25 views:—Figure 1 is a longitudinal sectional view of a furnace built in accordance with my invention; Fig. 2 is a sectional view taken on line 2—2 of Fig. 1; Fig. 3 is a perspective view of a stool or support for the 30 metal container disclosed in Fig. 1; Fig. 4 is a detail perspective view of a portion of one of the refractory heaters employed in my furnace; and Fig. 5 is a sectional view of a slightly modified form of furnace employing my principles.

1 indicates any suitable inclosing walls, 2 any suitable container for the metal to be melted, preferably in the form of a crucible as illustrated, and 3 any suitable cover 40 for the furnace. 4 indicates an opening with which the cover 3 is preferably provided, and 5 indicates an inlet for the fuel. All of the foregoing parts are or may be of the construction heretofore well known. 45 Surrounding the crucible 2 I preferably provide a plurality of refractory heaters 6 provided with checker-like projections 7, and having crossed channels 8 between said projections, through which the products of combustion may pass. Below the crucible 2 and the said heaters 6 I provide a support or stool 9 preferably of the form shown 50 in Fig. 3, and having supporting projections 10 of refractory material. This stool is suitably supported by the casing 1 as shown,

and the products of combustion freely pass between the supports 10 to enter the passages 8 in the heaters 6. Surrounding the stool 9 are additional heaters 12 provided with projections 13 provided with passages 60 14 for the passage of the products of combustion between the projections 13.

In my former patent above the vertical walls of the casing 1 immediately opposite the stool marked "e" in said patent were 65 located immediately below the heaters marked "j," or substantially in the position indicated by the dotted line 15 in Fig. 1 above. In the present application the bottoms of the passages 14 are located at a 70 considerable distance outside of the dotted line 14, and therefore a considerable space is provided through which the products of combustion may pass and become further oxidized before they enter the passages 8 75 of the heaters 6. In practice this is of a considerable advantage when using oil fuel, and for the reason that the combustion of oil, as is well known, is not so rapid, nor is it so perfect, as is the combustion of gas, 80 and therefore in metallurgical furnaces of this nature it is very desirable to get as perfect combustion as possible in order to secure a maximum heating effect. It will also be observed from Fig. 2 that the inlet 5 for 85 the fuel is tangentially arranged. This disposition of the inlet port enables the oil fuel to circulate around the passages 14 before entering the passages 8, and therefore permits a longer time for oxidation before the 90

crucible 2 is reached. The spacing of the supports 10 on the stool 9 is so chosen as to afford a large amount of space at the bottom of the crucible for this combustion to take place, and the result is that any heat 95 which may be liberated at the bottom of the crucible is directly available for melting the metal, while the more perfect combustion which takes place in the passages 8 insures that a maximum amount of heat is delivered 100 to the said crucible 2 before the gases escape through the opening 4.

In the form shown in Fig. 1 the products of combustion pass over the mouth of the crucible, and should it be left open as there 105 indicated, the suction from the escaping gases in some instances is liable to draw out the contents of the crucible, and should these contents be valuable such as gold precipitates like those obtained by the cyanid proc- 110

ess, the loss is considerable. In order to avoid such loss the crucible 20 of the form shown in Fig. 5 may be adopted, in which case the furnace will be correspondingly modified. That is to say, the bottle shaped mouth of the crucible 20 may be extended out of the furnace to one side of the opening 4, and a considerable space 21 left near the top of the furnace through which the products of combustion may circulate just before reaching said opening 4. In such form of furnace a heater plate 22 is also slightly modified in shape as shown. Otherwise, the principles of the furnace remain the same as in the preceding figures.

In operating a furnace such as that disclosed in Fig. 5 the gold precipitates may at intervals be fed in as the contents melt, until a full charge is obtained, when the contents may be discharged in the usual manner.

What I claim is:—

1. In a melting furnace the combination of a crucible; a stool provided with spaced supports on which said crucible rests; a plurality of heater projections and passages surrounding said crucible; and a plurality of heater projections surrounding said supports, the projecting ends of said last named projections being located at a greater distance from the central axis of the crucible than are the bottoms of the lowest of said passages, substantially as described.

2. In a melting furnace the combination of a crucible; a stool provided with spaced supports on which said crucible rests; a plurality of heater projections and passages surrounding said crucible; a plurality of heater projections surrounding said supports, the projecting ends of said last named projections being located at a greater distance from the central axis of the crucible than are the bottoms of the lowest of said passages; and an inlet adapted to deliver

fuel to the space between said supports, said supports being so spaced as to provide a free passage for said fuel to said last named projections, substantially as described.

3. In a melting furnace the combination of a crucible; a stool provided with spaced supports on which said crucible rests; a plurality of heater projections and passages surrounding said crucible; a plurality of heater projections surrounding said supports, the projecting ends of said last named projections being located at a greater distance from the central axis of the crucible than are the bottoms of the lowest of said passages; and a fuel inlet tangentially entering said furnace below said crucible and adapted to deliver fuel to the space between said supports and last named projections, substantially as described.

4. In a melting furnace the combination of a crucible having a mouth open to the atmosphere; a passage for the exit gases of combustion located to one side of said mouth; a stool provided with spaced supports on which said crucible rests; a plurality of heater projections and passages surrounding said crucible; a plurality of heater projections surrounding said supports, the projecting ends of said last named projections being located a distance from the central axis of the crucible greater than are the bottoms of the lowest of said passages; and a fuel inlet tangentially entering said furnace below said crucible and adapted to cause said fuel to rotate in the space between said supports and last named projections, substantially as described.

In testimony whereof, I affix my signature, in presence of two witnesses.

WILLIS W. CASE.
